CLAIM

The ornamental design for the firearm sight, as shown and described.

DESCRIPTION

FIG. 1 is an isometric view of a firearm sight.

FIG. 2 is a left side view of the firearm sight of FIG. 1.

FIG. 3 is a right side view of the firearm sight of FIG. 1.

FIG. 4 is a rear view of the firearm sight of FIG. 1.

FIG. 5 is a front view of the firearm sight of FIG. 1.

FIG. 6 is a top view of the firearm sight of FIG. 1; and,

FIG. 7 is a bottom view of the firearm sight of FIG. 1.

The broken lines illustrating features, forms, and the edges of planes depict portions of the firearm sight that form part of the claimed design.
